UNITED STATES PATENT OFFICE.

PERCY S. MARCELLUS, OF ORANGE, NEW JERSEY.

MOVABLE-TOP DESK.

1,244,523.

Specification of Letters Patent. Patented Oct. 30, 1917.

Application filed July 13, 1916. Serial No. 108,972.

To all whom it may concern:

Be it known that I, PERCY S. MARCELLUS, a citizen of the United States, residing at 23 Lincoln Place, Orange, county of Essex, and 5 State of New Jersey, have invented certain new and useful Improvements in Movable-Top Desks, fully described and represented in the following specification and the accompanying drawings, forming a part of 10 the same.

The object of this invention is to provide a desk in which the top is divided into sections, the side-tops being movable to expose filing-chambers within the upper part of the 15 desk, and which side-tops are constructed to shift laterally so that they may be moved, and access to the chambers attained, without disturbing any articles resting upon such movable tops.

Such a desk is generally formed with two 20 bodies connected together with an intervening space to admit the legs of the user beneath the central portion of the top, and my present invention, among other features, 25 includes the connection of the side-bodies by a tie-plate below the center-top and the pivoting of the center-top over such tie-plate so as to be reversible, and when turned bottom upward, to set at a lower level than 30 the top of the desk, to conveniently support a typewriter or similar instrument.

To inclose such typewriter when not in use, the center space is closed at the rear side by a back-plate, and at the front side by 35 a front-plate hinged to the reversible top.

The present invention includes a special 40 means of mounting the side-tops movably by means of links which swing in a vertical plane, to support the side-tops when moved laterally to uncover the filing-chambers; and this feature of the invention is applicable to desks having only a single side-body with movable top.

The invention includes various details of 45 construction which will be herein described, and pointed out in the claims.

The invention will be understood by reference to the annexed drawing, in which Figure 1 is a front elevation of the desk 50 with the left-hand top retracted.

Fig. 1^a shows the under side of one of the side-tops;

Fig. 1^b one of the links *l*, and Fig. 1^c a side-view of the rock-shaft for links *l*.

Fig. 2 is a plan of the desk with a portion 55 of the center-top broken away. Fig. 3 is a cross section at the middle line of the center-top.

Fig. 4 is a similar section with the center-top reversed.

Fig. 5 is a perspective view of the desk with the tops closed together.

Fig. 6 is a vertical section across Fig. 4 just within the inner sides of the left hand posts lettered *a*, the section line running vertically between such posts, and the left hand edge of the center top *f*; and Fig. 7 is a cross-section on line 7-7 in Fig. 1.

Figs. 3 and 4 show the center-top by dotted lines in several intermediate positions, 70 and in these figures the body of the typewriter is illustrated in dotted lines, as attached to the inner side of the center-top, which when reversed supports the typewriter in a working position below the top 75 of the desk.

The invention is illustrated in a desk with two side-bodies and intervening space, each of the bodies having a laterally movable top; but the invention is applicable to the 80 body of any desk requiring a laterally movable top.

Each of the side-bodies is shown formed with four posts *a* connected by cross-bars *b* and casing-walls *b'*, *b*², shown at the right-hand side of Fig. 2. Drawers *a'* are shown in the lower part of each body, and a chamber *c* in its upper part. The chambers *c* are closed normally by the side-tops *g*. The two bodies are connected by a tie-plate *d* 90 and a back-plate *d'*. The tie-plate is set sufficiently far below the center-top *f* to admit, if desired, a typewriter (illustrated by dotted lines *e*) between such top and tie-plate.

Within the casing-walls *b*² at each end of 95 the chambers *c* a space is provided for two links, *l*, *l'*, and a slotted guide-plate *h* is secured upon the top of such space, as shown in the left-hand chamber of Fig. 2, to guide the upper ends of the links, which are attached to the side-tops directly over such guide-plates.

The bottom end of each link *l* is jointed by a rock-shaft *i* in the lower end of a slot *j*

- in one of the corner-posts *a* of such chamber; and the bottom of each link *l'* is jointed by a pivot *k* to a cross-bar *k'* between adjacent corner-posts.
- 5 Each of the side-tops *g* is shown with a rectangular frame *m* forming a slide-box upon its under side, within which an extension-slide *m'* is movable, to increase the desk area when pulled out of the box.
- 10 The frame is provided at its ends, as shown in Fig. 1^a, with a cross-bar which forms the bottom of the box in which the slide is movable, and the upper ends of the links are pivoted to this cross-bar *m* by 15 pivots *n*.
- 15 The side-top is thus supported by two links at each end, and the links *l* are made to move in unison with one another by forming their pivots upon the opposite ends of 20 a rock-shaft *i* extended within the entire side-wall *b'* of the chamber *c*, and journaled in the inner side of the post *a* and squared near its ends to fit square holes in the lower ends of the links *l*.
- 25 The links are secured firmly to such squared portions, and thus move in unison so as to compel a parallel motion of the side-top, in its retraction from its normal position, to uncover the chamber *c*.
- 30 If the side-tops were unprovided with the slide *m'* the links *l* and *l'* would be jointed directly to them instead of to the bar *m* below the slide; but the construction shown permits the side-top to be furnished with the usual slide, and the slide carried therewith 35 when the side-top is retracted. The center-top *f* is pivoted to the side-bodies by hangers *c'*, and journals *c''*.
- 40 The space between the center-top and the bottom tie-plate *d* is closed, to protect the contents of such space, and by a front-plate *o* is hinged to the front portion of the center-top, so that when such portion is pressed downwardly to reverse the position of the 45 top, the front plate may be carried downward with it and the front of the space thus left entirely open for access to a typewriter.
- To leave space for the legs of the operator when the center-top is closed, this front-plate 50 *o* is sloped backwardly from the top to its lower end, and is held movably in such sloping position by a guide-bar *p* adjacent to the front edge of the tie-plate *d*. To permit the inversion of the center-top, its front 55 corner must clear the tie-plate *d* when the top is reversed, and to avoid fixing the tie-plate any lower than is necessary (and thus leave space for the feet of the operator) I shorten the center-top by forming the front 60 portion as a flap *f'* shown secured to the remainder of the center-top by a hinge *f''*, and the front-plate *o* is hinged to the under side of such flap, so that it may be tipped into a reversely sloping position when the 65 center-top is reversed, as shown in Fig. 4.

The hinging of such flap permits it to be folded backwardly, as shown at *f''* in Fig. 3, by contact with the guide-bar *p*, when the front edge of the center-top moves past such guide-bar.

In Fig. 3 the center-top and its flap are shown in two intermediate positions by dotted lines *o'* and *o''*, with the plate correspondingly shifted, and Fig. 4 shows the parts when the side-top is fully inverted; 75 blocks *g* being fixed upon the side-bodies to arrest the center-top when it is wholly reversed, and to support it thereafter when the typewriter *e* is moved forward upon the slides *e'*, as shown in Fig. 4.

Cross-bars *r* are shown in Figs. 1, 2 and 5, secured upon the side-bodies between the adjacent edges of the center-top and side-tops, such bars forming part of the flush surface of the desk-top when the side-tops 80 are drawn inwardly; and the front ends of these bars have recesses *r'* formed therein adjacent to the front corners of the flap *f*, with blocks *s* pivoted therein so that they may be turned outward, as shown in Figs. 85 1 and 3, beneath the front corners of the flap to support the same.

The blocks are arranged to swing or fall outwardly so as to set underneath the center-top when the latter is in its normal position. The blocks are pushed back, to reverse the top, and are also pressed back automatically by the corners of the top when the latter is returned to its normal position. The face of the block is notched at *t* 100 to fit against the corner of the top *f*.

A pocket *u* is shown formed in the back of the space above the tie-plate *d*, between the back-plate *d'* and the rear wall *v*, in which "stationery" for use by the typewriter operator can be conveniently kept, such space having a cover *u'* hinged upon the rear wall *v*, and shown in its open position in Fig. 3.

The pocket *u* is clearly shown in Fig. 2, 110 at the rear of the space in which the center-top can be inverted to support the typewriter. When in its normal position the rear edge of the center-top rests upon the blocks *g*, and is secured by a latch-bolt *w²* 115 provided with a handle *w⁴* for retracting it when desired. The latch-bolt is shown in Figs. 2 and 3 engaging a lock-plate upon the upper part of the back-plate *d'*.

Fig. 2 shows the interior of the chamber 120 *c* which is uncovered and shows partitions *c³* which may be disposed in any manner to form filing spaces for letters, bills, or other papers. The forward part of the chamber has partitions arranged therein to form 125 compartments marked "card-index" and "mailing list." These illustrations simply show the amount of available space which is secured by the ability to uncover these compartments. When the compartments are 130

thus uncovered the available desk room can be increased by withdrawing the slide m' entirely from its box m and using it as a cover for the chamber c , as indicated by dotted lines m^2 in Fig. 1.

To support the slide flush with the top of the desk, blocks w are shown projected from the face of the cross-bar r at its ends to sustain one edge of such slide, and tongues w' of metal are formed upon the side of the box from which the slide is withdrawn.

A small hole is made in the face of the bar r in the rear of the block w to receive the metal tongue w' when the side-top is re-

10 stored to its normal position. The block w at such time fits under the adjacent corner of the top g , so that the side-top may be closed against the bar r . By such use of the slide, the area of the desk-
20 top can be greatly enlarged when extra top-space is needed.

From the above description it will be seen that my improvements permit the utilization of all the space within the desk, and 25 by the retraction of the side-tops affords access at once to a large space, so that the contents of numerous files may be reached with great facility, and selections made from such large quantities without opening a
30 plurality of file-cases, drawers, or closets.

As the side-tops retain their horizontal position during their retraction to expose the contents of the chamber c , any books or papers lying upon such side-tops when it 35 becomes necessary to open the chamber c do not therefore need to be disturbed or shifted, but remain on the side-top when it is moved. When thus retracted, the side-tops also serve as an extension of the top to receive any 40 matter that may be lifted from the chamber, and thus enables an operator to sort, examine and arrange any papers taken from or placed in the chamber.

Fig. 1 shows that all the means for supporting the side-tops, during their movement laterally, is concealed within the chambers covered by such tops, and this effect is secured by locating the links l , l' in spaces within the ends of such chambers and pivoting the links to move within such spaces, and 50 forming the outer corner posts a^2 with slots j through which the links can swing outwardly, as shown at the left-hand end in Fig. 1.

55 This construction, as well as the fitting of a slide m' to a frame m attached to the under side of the side-top g , is obviously applicable to a desk having only one side chamber.

60 Having thus set forth the nature of the invention what is claimed herein is:

1. A desk formed with side-bodies and an intervening space between the same, a center-top supported movably over such space, 65 a side-top fitted to the top of each of the

side bodies, each side-top having a pair of links at each end extended downwardly within the side-bodies and operating to lift the top upwardly and then return it to its original level when uncovering the side-
70 bodies.

2. A desk formed with side-bodies having each a chamber in its upper part and an intervening space between the same with a center-top fitted movably to such space and a cross-bar upon each side body next the edge of the center-top, a side-top extended over each of the side-bodies to the said cross-bar and movable away from the same, each side-top having a pair of links at each end 75 extended downwardly within the said chamber and operating to move the side-top first upwardly and then downwardly to its original level in uncovering the said chamber.

3. A desk formed with side-bodies and an intervening space between the same, a center-top supported movably in such space and having journals upon the side-bodies and mounted reversibly upon such journals to support a typewriter, a side-top fitted mov-
85 ably over each of the side-bodies and movable laterally away from the center-top, each side-top having a pair of links at each end extended downwardly within the side-body and journaled to lift the top upwardly and 90 then return it to its original level when uncovering such side-body.

4. A desk having a body with posts at four corners and a chamber in its upper part with transverse spaces inside the casing walls 100 at the ends of the chamber, a top fitted movably to the body above the posts, a slotted plate forming a guide at the top of each of the transverse spaces, the outer corner-posts being similarly slotted, links pivoted at the 105 bottoms of the spaces in the outer halves of the said spaces and projected through the slotted plates and pivoted to the inner halves of the side tops, and operating to move the top first upwardly and then downwardly in 110 uncovering the said chamber.

5. A desk having a body with posts at four corners and a chamber in its upper part with transverse spaces inside the casing-walls at the ends of the chamber, a top fitted 115 movably to the body above the posts, and having attached to it a frame to support a slide, said frame resting normally upon the top of the body, and links pivoted to move within the ends of the chamber and jointed 120 to the said frame, and operating to move the said top first upwardly and then downwardly when moved laterally to uncover the said chamber.

6. A desk formed of side bodies having 125 each a chamber in the upper part and provided with separate movable side tops, a bottom tie-plate connecting the two bodies through an intervening space, a plate connecting the bodies at the back of such space, 130

a center top fitted movably over such space and having journals upon the side bodies and mounted reversibly upon such journals and adapted to support a typewriter, a 5 guide-bar in the bottom of such space and a front-plate hinged to the reversible top and guided by the said bar to normally close the front of the said space.

7. A desk formed of side bodies having 10 each a chamber in the upper part and provided with separate movable side tops, a bottom tie-plate connecting the two bodies through an intervening space, a center top fitted movably and normally flush with the 15 side tops over the said space and having journals pivoted upon the side bodies, the said top being reversible upon such journal, a guide-bar in the bottom of such space, a flap hinged upon the front edge of the center top, a front plate hinged to the said flap 20

and guided by the said bar to normally close the front of the said space, the flap being adapted to clear the bottom tie-plate when the center top is reversed.

8. A desk having a body with posts at 25 four corners and a chamber in its upper part with transverse spaces inside the casing-walls at the ends of the chamber, a top fitted movably to the body above the posts, links pivoted to move within the ends of the chamber and jointed to the said top, and the corresponding links at opposite ends of the chamber being connected rigidly to a rock-shaft, whereby the said links at the opposite ends of the chamber move in unison with 30 35 one another.

In testimony whereof I have hereunto set my hand.

PERCY S. MARCELLUS.
